LOOM SELVAGE DEVICE

Carl D. Brown, Hopedale, Mass., assignor to
Draper Corporation, Hopedale, Mass., a corpora-
tion of Maine

Application November 5, 1940, Serial No. 364,441

8 Claims. (Cl. 139—195)

This invention pertains to looms and more particularly relates to selvage devices therefor.

It is general practice in weaving cloth to add extra ends in the selvage to carry the strain or jerk of the filling as the shuttle is picked across to the opposite side of the loom. Various types of selvage devices have been employed to eliminate the necessity of having the extra ends for the protection of the filling. Such prior devices usually comprise a support mounted on the loom temple head and having a needle or loop retaining finger pivotally connected thereto and when in operative position projecting down past the selvage at the point where the filling is beaten up, so that the shuttle draws the filling around the needle until it arrives at the box on the other side, when the needle is raised to inoperative position.

In such devices it is essential that the needle, when raised to inoperative position, not interfere with the proper operation of the reed or other parts of the loom.

Accordingly it is the principal object of my invention to provide in a loom, a selvage device comprising a support including a housing adapted to be attached to the loom temple, a reciprocating member mounted in the housing and having a needle at one end and resilient means for holding the reciprocating member in its rearward position, which reciprocating member shall be connected to the housing by a pin and slot connection so constructed and arranged as to give the member a swinging movement in a vertical plane and then a reciprocating movement in a horizontal plane whereby the needle will be first lifted clear of the warp threads and then moved forwardly out of the way of the reed.

The foregoing and other objects of the invention are accomplished in the construction illustrated on the accompanying drawing, of which:

Fig. 1 is a perspective view of a portion of one end of a loom having my invention applied thereto;

Fig. 2 is a view in cross-section taken on line 2—2 of Fig. 1 and showing the needle in its operative position;

Fig. 3 is a view similar to that of Fig. 2, but showing the needle raised to inoperative position; and,

Fig. 4 is a view similar to that of Fig. 2, but shows the needle raised to inoperative position and moved to its forward position.

As the invention is applicable to any type of loom wherein there is a frame, a lay, shed form-

ing mechanism, a shuttle and shuttle picking mechanism, and other usual instrumentalities, it is considered unnecessary to illustrate such features which are familiar to those skilled in the art.

Accordingly only a small portion of the right hand side of a loom is shown, including the right hand loom temple on which the selvage device is mounted. As the construction is generally similar at both sides of the loom it is considered sufficient only to refer to that of one side.

On the drawing is shown a portion of the usual lay 1, hand rail 2, reed 3, shuttle guard rail 4 and the right hand temple 5.

15 The selvage device of my invention is shown as mounted on the temple head and may comprise a housing indicated generally at 6. The housing may be formed as a single integral piece or may be made in two separate pieces as shown on the drawing. The housing may comprise a pair of spaced plates 7 and 8. These plates are held apart by the spacing lugs 9 and 10 which are formed integral with plate 7. A bolt 11 secures plates 7 and 8 together. A pin 12 formed integral with plate 8, projects into an opening in plate 7, for a purpose to be hereinafter described. Plate 8 has formed integral therewith and substantially at right angles thereto an attaching portion 13. The attaching portion 13 has an elongated opening therein for the reception of a bolt 14 by means of which the housing is adjustably attached to the head 15 of the temple 5. The plate 7 has an extension 16 extending outwardly from its upper edge for a purpose later to be described.

By means of the spacing lugs 9 and 10 and the bolt 11, plates 7 and 8 are firmly held together in parallel spaced apart planes forming therebetween a guide-way or passage way 17.

20 Mounted in guide passageway 17 in housing 6 for reciprocatory movement therein is a member 18. Member 18 has an upstanding lug 19 at one end. Lug 19 has an opening therein for the reception of the threaded arm 20 of a bunter 21. Bunter 21 is adjustably secured to lug 19 by means of lock nuts 22, 23. Member 18 at its other end has an opening 24 for the reception of a needle bar 25. Needle bar 25 is adjustably secured to member 18 by means of set screw 26. 25 Needle bar 25 may carry one or more spaced needles 27. Member 18 has formed on its bottom side and intermediate its ends an open ended slot or recess 28. Pin 12 which extends transversely of the guideway 17 is located within slot 28 and bears against the upper wall of

slot 28 thereby guiding and supporting member 18 in its reciprocatory movements; in addition pin 12 forms a pivot about which member 18 may be swung in a vertical plane, that is when member 18 has moved rearwardly and pin 12 rests against the closed end of slot 28.

The bolt 11 in addition to its function of securing plates 7 and 8 together, acts as a stop to limit the downward movement of member 18 as it swings in its vertical arc. Bolt 11 also acts as a supporting and guiding surface for member 18 on its reciprocatory movement. The extension 16 on plate 7 acts as a stop to limit the upward swing of member 18.

A coiled spring 29 has one end secured to extension 16 as at 30 and the other end secured to lug 19 as at 31. The function of spring 29 is to urge member 18 rearwardly in guideway 17 until pin 12 abuts the closed end of slot 28, then the spring causes member 18 to swing about pin 12 as a pivot, the rearward end of member 18 which carries the needle bar moving downwardly until it abuts bolt 11.

The operation of the device is as follows:

The device is adjustably mounted on the temple so that when the needle 27 is in its lowermost or operative position, the point of the needle is between the warps, adjacent the selvage just behind the beaten in weft. When the shuttle is picked across the warps from that side or selvage of the fabric, the weft will loop about the needle and will be held thereby against being pulled inwardly. When the lay moves forwardly to beat in the weft the shuttle guard rail 4 will engage the bunter 21 and against the pull of spring 29 will swing member 18 about pin 12 as a pivot thereby raising the needle 27 upwardly from the warp. When the forward end of member 18 abuts the stop extension 16, the upward swinging movement stops and as the shuttle guard rail 4 continues to move forwardly member 18 will slide forward in guideway 17 against the pull of spring 29. Member 18 in its forward movement slides on and is supported by pin 12. Upon the rearward movement of shuttle guard rail 4, the spring 29 slides the member 18 rearwardly until pin 12 abuts the closed end of slot 28 whereupon the spring causes member 18 to turn about pin 12 as a pivot thereby lowering the needles 27 into operative position. When the needles are in operative position the rearward end of member 18 abuts the bolt 11 which acts as a stop limiting the downward movement of member 18.

I claim:

1. A loom selvage device comprising a housing having a longitudinal guideway therein, a pin extending transversely of said guideway, a member slidably mounted in said guideway and having an elongated portion bearing on said pin, a bifurcation adjacent one end of said elongated portion and forming a stop for said slidably mounted member, a needle mounted on the free end of said elongated portion, means for moving said member transversely of said pin and for swinging said member in a vertical plane about said pin as an axis.

2. A selvage device for a loom including a lay and a shuttle guard rail, said device comprising a housing adjustably mounted on said temple, said housing having a longitudinally extending guideway therein, a pin extending transversely of said guideway, a forked member mounted in said guideway and engaging said pin, a needle adjustably mounted on said forked member at its rear end, resilient means for moving said forked

member rearwardly along said pin and in a vertical plane about said pin as a pivot and means carried by said forked member for engagement with said guard rail on the forward beat of the lay whereby said forked member will be swung upwardly about said pin as a pivot and then moved forwardly.

3. In a selvage device for a fly shuttle loom including a lay, the combination of a housing having a guideway therein extending longitudinally of the loom, a member mounted in said guideway for movement forwardly and rearwardly of said loom and for swinging movement in a vertical plane longitudinally of the loom, a needle mounted on the rear end of said member and adapted for movement from operative to inoperative position, resilient means for giving said member consecutively a rearwardly sliding movement and then a downwardly swinging movement independent of said rearwardly sliding movement and means engageable by some part of the lay for giving said member consecutively an upwardly swinging movement and then a forwardly sliding movement independently of said upwardly swinging movement, whereby said needle is lifted above the warp and moved forwardly to inoperative position upon the forward beat of the lay and is moved rearwardly and lowered into the warp into operative position on the rearward beat of the lay.

4. A loom selvage device comprising a supporting member, a needle carrying member, and means pivotally and slidably connecting said members together, said connecting means being so constructed and arranged as to guide said needle carrying member consecutively through a swinging movement in a vertical plane and then in a rectilinear reciprocatory movement, independent of said swinging movement, in a horizontal plane and means for moving said needle carrying member.

5. A loom selvage device comprising an attaching and supporting member, a movable member having loop retaining means at one end thereof, said movable member being slidably mounted on said supporting member for movement into and out of a pivotal position thereon, means for moving said movable member towards and from said pivotal position and means for swinging said movable member in a vertical plane while in the pivotal position.

6. A selvage device for a loom including a lay said device comprising a support, a needle carrying member pivotally and slidably mounted on said support, resilient means for slidably moving said needle carrying member into pivotal engagement with said support and for swinging said member downwardly in a vertical plane about its pivot, whereby said needle is brought into operative position, means carried by said member and adapted to be engaged by said lay on its forward beat for swinging said member upwardly in a vertical plane about its pivot and slidably moving said member forwardly out of pivotal engagement with said support whereby said needle is raised from operative position and moved forwardly to inoperative position.

7. In a loom selvage device, the combination of a housing having a longitudinal guideway therein, a needle carrying member mounted in said guideway, said member being connected to said housing by a pin and slot connection, said connection being so constructed and arranged as to guide said member consecutively in a swinging movement in a vertical plane about said pin

and then in a rectilinear reciprocatory movement, independent of said swinging movement, in a horizontal plane and means for moving said member.

8. A selvage device for a loom including a lay and a shuttle guard rail, said device comprising a housing having a guideway therein, a pin extending transversely of said guideway, a reciprocatory member mounted in said guideway, said member having an open ended slot on its bottom edge engaging said pin, a needle adjustably connected to the rear end of said member, a coiled spring connected at one end to said housing and at the other to the forward end of said member,

5 said spring acting to move said member rearwardly in said guideway, until said pin engages the closed end of said slot whereupon said spring acts to swing said member in a vertical plane about said pin as a pivot, a stop to limit the downward swing of said member, a bunter adjustably connected to the forward end of said member, said bunter being adapted to be engaged by said shuttle guard rail on the forward beat of the lay whereby said member will swing upwardly about said pin as a pivot and then moved forwardly in said guideway and a stop to limit the upward swing of said member.

CARL D. BROWN.
